PARLOR STOVE.

No. 17,219.

Patented Mar. 29, 1887.

UNITED STATES PATENT OFFICE.

GURDON G. WOLFE, OF TROY, NEW YORK, ASSIGNOR TO THE FULLER & WARREN COMPANY, OF SAME PLACE.

DESIGN FOR A PARLOR-STOVE.

SPECIFICATION forming part of Design No. 17,219, dated March 29, 1887.

Application filed February 10, 1887. Serial No. 227,922. Term of patent 7 years.

To all whom it may concern:

Be it known that I, GURDON G. WOLFE, of the city of Troy, county of Rensselaer, State of New York, have invented and produced a new and useful Design for Parlor-Stoves, of which the following is a specification.

My invention relates to a design for the ornamental form and surface ornamentation of parlor-stoves, as shown in the two accompanying photographs, forming a part of this specification, of which—

Figure 1 is a front view, and Fig. 2 a side view, and in which the several parts of the stove are designated by letters and the detail ornamentation by numbers, and as follows:

The leading features of my design consist in the ornamented ash-pit and base, the ornamented body, and the top, as hereinafter will be more fully stated, and as shown in the illustrations forming a part hereof.

The letter T designates the top of the stove, which consists of a flattened dome, 1, ornamented with a series of reversing scrolls, 2, arranged within radially-fretted arch-form figures 3, and the bottom band-molding, 4. The platform of the stove-top 5, on which the dome rests, is flat, and is ornamented with radially-arranged flutings 6, and the edge of the top, where overhanging the body part, has 30 a beveled band-molding, 7, having an out-curve, 8, between its ends.

The letter B designates the body part of the stove, and b² a panel formed therein at the front, immediately beneath the overhang of the top, and above the upper series of doors. This panel b² consists of two end rosette figures, 9, surrounded by a circular fillet, a center figure, 10, surrounded by an elliptical border-fillet, and having within the ellipse the figure, 11, of an archer mounted on a lion, with a background of scroll-work, 12. Within this panel b², at the corners and between the circular fillets, are foliated figures 13. This panel is further ornamented with a fretted top and end molding, 14, and at the bottom by a horizontal molding of guilloche, 15.

The letters D² designate the upper doors of the stove, and f' the frame thereof, the latter being divided off into panes by means of stiles 16 and horizontal sash-bars 17. The doors D² are each ornamented with vine-form reversing

convolute scrolls 18, 19, 20, and 21, which scrolls have ornamental fronds, and are produced by an upper bifurcation, 22, a lower bifurcation, 23, and a side bifurcation, 24, and all of which in each door are arranged within the frame f' and upon the vertical stiles and horizontal sash-bar thereof, and equally opposite the central intersection of the sash-bar and stile.

The corners of the stove-body B are ornamented with the buttresses p', which at the upper part are mounted with a foliated cap, 25, and at the bottom with a foliated plinth, 26. The upper part of each of the buttresses 65 is ornamented with flutings and merged pencils 27, the middle part of the buttresses with twisted flutings 28, and the bottom part with leaf ornaments 29, the several ornamented parts of the buttresses below the caps and 70 above the plinths being divided off horizontally by ornamented rings 30.

The lower door, d', of the front has the frame f' divided off by intersecting vertical stiles 31 and a horizontal sash-bar, 32, into 75 panes, and at each side of this central stile there is arranged interiorly vine-form bifurcating scrolls 33 33, each having two reversing convolute scrolls, 34 and 35, the latter one at its side making a fronded connection with the inside end of the door-frame, and the curl 36 making a fronded connection with the top and bottom of the frame interior edge, with the scrolls 33 arranged in reversing curve at each side of the center stile.

The letter N designates the ash-pit section, and W the top of the latter, which is ornamented with the fretted molding 50 on its outer edge. The door at the front of the ash-pit section (indicated at n²) is ornamented with a series of wave-line fan-form curves, 51, made in relief and terminating in scrolls, a central rosette figure, 52, and an arch-form figure, 53. The corners of the ash-pit section N are each ornamented with two Egyptian columns, 54, 90 having a fluted cap, 55, and fluted plinths 56, and intermediate twisted flutings, 57. The ash-pit section at the sides is ornamented with the same ornamentation as the ash-pit doors and the ash-pit-section front, with the addition thereto of the griffin-form brackets 58 and the fretted rail 59.

The base of the stove D, below the ash-pit, at the front and sides, is ornamented with the fretted, beveled, downwardly and outwardly projected molding 60, and the receding fretted reversing ovolو molding 61, and the filleted and fretted molding 62 below the latter.

The sides of the stove are alike, and each has the same arrangement of corner buttresses as the front.

10 The letter P designates a panel formed in each of the sides below the overhang of the top, and this panel has a narrow and continuous scalloped border, 63, three uniform filleted rosette figures, 64 64 64, and intermediately-placed foliated ornaments 65.

15 The upper doors, d⁴, of the sides of the stove each have a frame, f³, divided off interiorly into panes by means of vertical sash-stiles 66 66 and a horizontal sash-bar, 67, and these doors within 20 the frame, which is filleted, are interiorly ornamented with bifurcating scrolls 68, the curl of the upper and lower bifurcation thereof of each of them being convolute at 69, the side curls, 71, being from their bifurcation 25 curved to attach to the inner edge of the frame-sides and the horizontal sash-bar thereat, and having fronds upon them throughout their length, with the interlacing vine-tendrils 80 in each upper and lower middle panes. At the 30 intersection of the stiles and sash-bars of these doors d⁴ there is a rosette figure, 72.

35 The lower side doors, d⁵, have a frame, f⁴, divided off into panes by vertical sash-stiles 81 81 and horizontal sash-bar 82, and the frame interior is ornamented in each pane by horizontally-arranged elliptical scrolls 83 and rosettes 84 at the intersection of stiles and sash-bar.

40 The feet F are ornamented with the scroll figures 73 at their sides, the griffin's head 74, placed centrally at the front, and the tarsal-part furrows t¹, projected downwardly and frontwardly from beneath the overhanging front portion of the body part b⁶.

45 Having thus described my design, what I claim, and desire to secure by Letters Patent, is—

1. In a design for a stove, the top T, consisting of the flattened dome 1, ornamented 50 with a series of reversing scrolls arranged within beaded arch-form figures, the platform 5, ornamented with radially-placed flutings, and beveled band-molding 7 on the edge of the platform, having an outcurve thereat, as described and shown.

2. In a design for a stove, the panel b², arranged on the stove-body beneath the top, consisting of the filleted and rosette figures, the filleted central elliptical figures containing 60 the figure of an archer mounted on a lion, with a background of scroll-work, with foliated ornaments at the corners and between the rosettes, and the center elliptical-form figures, as shown and described.

65 3. In a design for a stove, the doors D², each

having the frame f², and consisting of the stiles and sash-bars dividing said frame into panes, and convolute scrolls 18, 19, 20, and 21, arranged within said door-frame and upon the sash-bars and stiles, as shown and described. 70

4. In a design for a stove, the corner buttresses, p¹, consisting of a foliated cap at the top, a foliated plinth at the bottom, a detail of fluting and pencils below the cap, twisted fluting below the fluting and pencils, and foliated 75 ornamentation immediately above the plinths, with rings arranged between the several details before named, as shown and described.

5. In a design for a stove, the door d², consisting of the frame f², divided off into panes 80 by vertical stiles and horizontal sash-bars, and the bifurcating and reversing scrolls 33, each having the convolute curls 34 35, and arranged within the frame with reference to the latter, the sash-bar and stiles, as shown and described.

6. In a design for a stove, the ash-pit door n², consisting of the relief wave fan-formed and curved details 51, terminating in end scrolls, a central rosette figure, 52, and an 90 arch-form ornament, 53, as shown and described.

7. In a design for a stove, the side doors, d⁴, consisting of the frame f³, divided off by vertical stiles and a horizontal sash-bar, and the 95 vine-form scrolls 68 68, each having convolute top and bottom curls, and side curls with interlacing top and bottom vine-tendrils, 80, within the middle panes, as shown and described. 100

8. In a design for a stove, the ornamental form and surface ornamentation of the stove-base D below the ash-pit section N, consisting of the upper fretted outwardly-projected and downwardly-beveled molding, 60, and the 105 recessional fretted reversing ovolو molding 61 below the said upper molding, the filleted and bottom band-molding, 62, as shown and described.

9. In a design for a stove, the side panel, P, 110 consisting of a narrow and continuous scalloped border, 63, three uniform rosette figures, 64 64 64, and the foliated ornaments 65, as shown and described.

10. The design for a stove, consisting of the 115 shape and ornamentation of the top T, the body B, ornamented with the panel b² at the front, beneath the top, the buttresses p¹, the front doors, D² and d², the upper side doors, d⁴, and the lower side doors, d⁵, the shape and 120 ornamentation of the ash-pit section N, and the shape and ornamentation of the feet F, as shown and described.

Signed at Troy, New York, this 7th day of July, 1886, in the presence of the two witnesses whose names are hereto written.

GURDON G. WOLFE.
